UNITED STATES PATENT OFFICE.

ELLIS F. EDGAR, OF WOODBRIDGE, NEW JERSEY.

STEAM-TURBINE.

980,504.

Specification of Letters Patent.

Patented Jan. 3, 1911.

Application filed September 13, 1910. Serial No. 581,752.

To all whom it may concern:

Be it known that I, ELLIS F. EDGAR, citizen of the United States, and resident of Woodbridge, in the county of Middlesex and State of New Jersey, have invented certain new and useful Improvements in Steam-Turbine Engines, of which the following is a specification.

Figure 1 is an end elevation mostly in full and a part in a section at line 1-1 in Fig. 2. Fig. 2 is a side elevation part in full and part in section.

I had in view in designing this engine an engine capable of using a working pressure up to five thousand (5,000) pounds or more with high economy as hereinafter set forth.

Details of construction.—1— side casing, 2— end casing, 3— main driving shaft, 4— long moving blades, 5— reacting moving blades, 6— guides, 7— steam chest, 8— ring casing of steam chest, 9— primary feed valve, 10— automatic controlling feed valve, 11— opening and closing cam, 12— ball governor, 13— main steam line from generator, 14— steam connection from valve 9 to valve 10, 15— exhaust pipes, 16— steam connection from main line to primary feed valve 9, 17— driving wheel connecting long moving blades 4 to main driving shaft 3, 18— driving wheel connecting reacting and moving blades 5 by gearing to main driving shaft 3, 19— feed line from automatic controlling valve 10 to steam chest 7, 20— teeth on inner edge of driving wheel 18, meshing with small gear wheel 21, 22— shaft carrying small gear wheels 21 and 23, 23— small gear wheel meshing with gear wheel 24 connected to main driving shaft 3, 25— exhaust chamber, 26— roller bearing for driving wheel 18.

General description.—This engine is constructed preferably with a steam chest constructed in a heavy ring casing surrounding a main driving shaft having connections to spreader guides terminating in a long narrow mouth whereby the steam is delivered in a wide sheet on long moving blades 4 so arranged as to form long diverging nozzles between said blades whereby the steam is expanded many times before being exhausted on reacting and moving blades 5, which are spaced closer together than the exhaust space between moving blades 4.

I do not confine myself to the spacing shown here between reacting and moving blades 5 as I may contract the space between

these blades at their exhaust end so as to offer more resistance to the exhaust from moving blades 4. Moving blades 4 and 5 move in opposite directions, but operate main driving shaft 3 in the same direction. The object in not having reacting blades 5 stationary is to utilize the friction produced by the exhaust from moving blades 4 while passing over the surface of blades 5.

I do not confine myself to having my steam chest located in the center around the driving shaft as I may place the steam chest just inside of the outer casing especially in the multiple steam chest types where there would be more than two rows of blades as shown in this case. I show here one row of blades on each side of driving wheel 17, each exhausting on a row of reacting and moving blades 5. I show driving wheel 17 extending almost to outer casing 1 leaving only a slight clearance forming a partition in exhaust chamber 25. These blades might extend the full width of exhaust chamber 25 having long bolts running through them securing them to driving wheels 18 or, they might be cast on one side of driving wheels 18, or they might be otherwise secured, either on one or both sides as driving wheels 18 might be arranged differently, especially when the steam chest would be located just inside of the outer casing where the exhaust steam chamber 25 is now located and the exhaust steam chamber would then be located in the center around driving shaft 3.

The manner in which high economy is obtained in this engine is as follows, by first passing the steam from the generator through primary valve 9, which is composed of a balanced cylinder puppet valve operated by an opening and closing cam, this valve 9 delivers steam to valve 10, which is also composed of a balanced cylinder puppet valve which is operated by an automatic governor. The object of the opening and closing cam on valve 9 is in the case of a multiple steam chest type that each steam chest will be equipped with one automatic valve 10 and one primary feed valve 9 and only a sufficient number of valves 9, will be opened by the opening and closing cams to take care of the load as the object of these valves is to always deliver boiler pressure to valves 10, thereby giving economy if properly used after leaving steam chest 7. Valves 10 are to take care of any sudden change of load to prevent the engine running away by cut-

ting off the steam automatically as the valves will be arranged to cut out at different speeds so that only a sufficient number will remain open to take care of the load after the steam leaves steam chest 7 to spreader guides 6, the steam is spread in these guides to a wide thin sheet whereby the steam is delivered in this form on wide long moving blades and expanded to any desired pressure when entering upon the reacting moving blades. In this manner this engine can be built to handle any desired pressure economically by expanding the steam and eliminating the friction on the reacting and moving blades as set forth. Preferably I would connect the long moving blades 4 secured to driving wheel 17 direct to driving shaft 3 and reacting and moving blades 5 secured to driving wheel 18. I would connect to driving shaft 3 by gearing substantially as shown. It would be necessary to have several of the small gear wheels 21 meshing into teeth 20 on the inner surface of driving wheel 18 to properly support driving wheel 18. Roller bearing 26 is a further support for driving wheel 18.

Having described my invention what I claim as new and desire to secure by Letters Patent is:

- 30 1. A steam turbine engine having one or more steam chests, spreader guides connected thereto and terminating in a long narrow mouth, long moving blades with diverging curved surfaces receiving steam therefrom and forming long curved diverging nozzles, whereby the steam is expanded many times before exhausting from said nozzles, substantially as set forth.
- 25 2. A steam turbine engine having one or more steam chests connected to spreader guides terminating in a long narrow mouth, said guides so formed as to spread the steam

in a thin sheet at the mouth of said guides leading to long moving blades with a curved surface so arranged as to form long curved 45 diverging nozzles between said long moving blades whereby the steam is expanded many times before exhausting from said nozzles on reacting moving blades receiving steam from said long blades and mounted on a wheel secured to a driving shaft, substantially as set forth.

3. A steam turbine engine having one or more steam chests connected to guides leading to long moving blades with long diverging surfaces so arranged as to form long diverging nozzles between them said long moving blades receiving steam from said guides and exhausting on reacting moving blades secured to a driving wheel said driving 50 wheel being carried on roller bearings and an exhaust chamber entirely surrounding said reacting moving blades at their exhaust end, said reacting blades and said long moving blades being connected to a driving shaft all 55 substantially as set forth.

4. A steam turbine engine having long moving blades with diverging surfaces forming long diverging nozzles between them and guides so arranged as to deliver steam in thin sheet form on said long moving blades at the contracted end of said long diverging nozzles whereby the steam is expanded many 60 times before exhausting at the exhaust end of said long diverging nozzles substantially 65 as set forth.

Signed at New York in the county of New York and State of New York this 10th day of Sept. A. D. 1910.

ELLIS F. EDGAR.
